TOY LAUNCHING GUN

Frederick R. Parker, Long Beach, Calif.

Application April 21, 1958, Serial No. 50,541

Term of patent 7 years

(Cl. D34—15)

Figure 1 is a side elevational view of a toy launching gun showing my new design;

Figure 2 is a top plan view;

Figure 3 is a front end view; and

Figure 4 is a rear end view.

The broken line showing of a rotary wing flying toy in Figure 2 is for illustrative purposes only.

I claim:

The ornamental design for a toy launching gun, substantially as shown and described.
